(57) **CLAIM**

The ornamental design for a bail for optical transceiver, as shown and described.

DESCRIPTION

FIG. 1 is a top, front and left side perspective view of a bail for optical transceiver showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a cross-sectional view taken along line 8-8 in FIG. 2;

FIG. 9 is a top, front and left side perspective view thereof in use condition and on a reduced scale; and,

FIG. 10 is another top, front and left side perspective view thereof, in use condition.

The features shown in broken lines in the drawings depict environmental subject matter only and form no part of the claimed design. The dash-dotted lines denote the boundary of the claim and form no part of the claimed design.

1 Claim, 10 Drawing Sheets
